UNITED STATES PATENT OFFICE.

TALBOT C. DEXTER AND VERNON GARNER, OF PEARL RIVER, NEW YORK, ASSIGNEES,
BY DIRECT AND MESNE ASSIGNMENTS, TO DEXTER FOLDING COMPANY, OF PEARL
RIVER, NEW YORK, A CORPORATION OF NEW YORK.

PAPER-FEEDING MACHINE.

959,319.

Specification of Letters Patent. Patented May 24, 1910.

Application filed February 25, 1909. Serial No. 479,957.

To all whom it may concern:

Be it known that we, TALBOT C. DEXTER and VERNON GARNER, both citizens of the United States, and residents of Pearl River, 5 in the county of Rockland and State of New York, have invented certain new and useful Improvements in Paper-Feeding Machines, of which the following is a specification.

The present invention relates particularly 10 to improvements in the sheet delivery devices of automatic paper feeding machines in which a pile of sheets is supported upon an automatically elevated table and the successive sheets are fed forward by suitable 15 feeding off devices and then delivered from the pile by suitable sheet delivery mechanism, usually in the form of drop roller mechanism, to be delivered thereby to some suitable sheet conveying mechanism which supplies the successive sheets to a printing press, folder, ruling machine or other machine designed to operate upon sheets of paper.

The main object of the present invention 20 is to provide such an automatic paper feeding machine with a simple and effective mechanism at the delivery end of the machine for accurately detecting the presence of more than a single thickness of sheets, and in the event of the presence of two or 25 more sheets, to move back slightly the under sheet or sheets while the top sheet is fed from the pile by the drop roller delivery mechanism.

The present improvements are particularly 30 designed for feeding extra heavy or thick sheets of paper such, for instance, as cardboard, which presents unusual difficulty in separating and feeding.

The present invention has been designed 35 in the form of an attachment which may be applied to the ordinary automatic paper feeding machine now on the market, but it will of course be understood that it is not intended to limit the scope of the invention to its attachment form. The caliper and separating devices comprise a lower roller operating beneath the plane of feed of sheets and rotating with its upper periphery moving rearwardly or toward the pile of sheets, 45 an upper caliper member either in the form of a roller or shoe movable toward and away from the lower roller and operating through adjustable means by which its limit of approach toward the lower roller can be

regulated to a nicety, and one or more lower 55 caliper members or shoes which are yieldingly mounted beneath the plane of feed and are supported just above the upper periphery of the lower roller, so as to normally prevent the engagement of said lower 60 roller with the lower surface of a single sheet.

It will be understood that the usual feeding off and delivery devices are employed in connection with the improved caliper and 65 separating devices. In operation, the feeding off devices move the top sheet of the pile through the caliper and separating devices and a sheet delivery mechanism comes into operation immediately after the operation 70 of the caliper and separating devices. In the event of two or more sheets being fed forward to the caliper and separating devices, the yieldingly mounted lower caliper members will be forced 75 downward by the action of the lowering of the upper caliper members so as to force the lower sheet or sheets into engagement with the upper periphery of the lower separating rollers, with the result that the lower 80 sheet or sheets will be positively moved rearwardly toward the pile, while the upper sheet is moving forwardly into position to be taken by the delivery mechanism. The caliper and separating devices complete 85 their operation approximately simultaneously with the feeding off devices and just prior to the action of the sheet delivery drop rollers which take the single separated top sheet and feed it from the pile in the usual 90 manner.

In order that our invention may be fully understood, we will first describe the same with reference to the accompanying drawings and afterward point out the novelty 95 more particularly in the annexed claims.

In said drawings, Figure 1 is a vertical longitudinal sectional view of a paper feeding machine showing the application of the present invention, parts of the machine being omitted for the sake of clearness. Fig. 2 is a similar view on a larger scale of the caliper and separating devices and drop roller delivery mechanism, the parts being shown in the position assumed at the start 100 of the caliper and separating operations. Fig. 3 is a similar view showing the parts in the position assumed at the completion 105

of the caliper and separating operations and at the commencement of the delivery of the sheet by the drop roller mechanism. Fig. 4 is a rear vertical elevation of the parts of the mechanism shown in Figs. 2 and 3 in the position of Fig. 2. Fig. 5 is a sectional plan view of the preferred form of the upper caliper member showing the arrangement of gears driving the upper caliper roller. Figs. 6 and 7 are detail vertical sectional views illustrating the operation of the sheet caliper and separating devices. Fig. 8 is a diagrammatic plan view illustrating the arrangement of the main parts of an automatic paper feeding machine having the present improvements applied thereto. Fig. 9 is a detail vertical sectional view showing a modified form of upper caliper member.

As stated above, the specific embodiment of the present invention illustrated in the accompanying drawings, comprises an attachment for an automatic paper feeding machine such as is now in common use. It will be understood that the following reference to the well known parts of such a feeding machine is intended in the broadest sense as illustrating the general features of a machine which would ordinarily be used in connection with the present improvements.

The machine may consist of any suitable frame work including for instance side frames such as 1, cross frames or rails such as 2, tie rods or bars such as 3, and the usual transverse shafts operated through suitable gearing in a well known manner.

A pile of sheets indicated by P is mounted upon a suitable automatically elevated table or support.

5 is a constantly driven shaft arranged transversely of the feeding machine at its delivery end. Said shaft 5 carries a suitable number of the usual under feed rollers 6, with two or more of which coöperate the usual drop rollers 7 freely journaled in the rear ends of rock arms 8 mounted upon a rock shaft 9 and actuated by an upwardly projecting rock arm 10 carrying at its upper end an anti-friction roller 11 which runs in peripheral contact with the controlling and operating cam 12 keyed to the main cam shaft 20 of the feeding machine. This drop roller mechanism is of the ordinary construction.

In this automatic paper feeding machine, it is quite common to employ at the rear end of the pile of sheets and at opposite sides thereof independent sheet buckling mechanisms which serve to preliminarily separate the successive sheets at the rear edge. In the use of the machine equipped with the improved caliper and separating devices hereinafter explained, the said buckling features are not necessarily em-

ployed, but it is very desirable to utilize the holding down feet or clamps as tail grips for the purpose of holding back the several sheets beneath the top sheet, as such top sheet is delivered from the pile by the drop roller delivery mechanism.

In Figs. 1 and 8 of the drawings, the reference numeral 15 indicates any suitable form of tail grips, which as stated, may be the holding down feet of the ordinary sheet buckling mechanisms, one suitable form of which is shown and described in Patent No. 747,865 granted December 22nd, 1903. These tail grips may, however, be especially designed to be used only in a machine equipped with the present caliper and separating devices. The specific mechanism for operating the tail grips is not shown in the drawings, but will be well understood by those skilled in the art, it being clear that the operating mechanism for said tail grips must be so timed that the tail grips will operate to engage the pile alternately with the feeding off devices so as to hold the pile during the time that the successive sheets are being delivered from the pile by the drop roller delivery mechanism.

Any suitable form of feeding off devices may be employed. Machines of this type usually have two sets of feeding off devices arranged in parallel vertical longitudinal planes above the pile of sheets so as to feed the successive sheets forward as nearly as possible in squared or registered position.

In Figs. 1 and 8 of the drawings, the reference numerals 25 indicate some suitable form of feeding off devices designed to move forwardly the successive top sheets from the pile into the control of the caliper and separating devices and into position for the operation of the drop roller delivery mechanism. The specific form of feeding off device illustrated is not described herein because it is fully set forth in Patent No. 768,979, granted August 30th, 1904.

It will be understood that the above described features of an automatic paper feeding machine are quite common in the art and are not specifically claimed in the present case excepting in combination with the features of the improved sheet caliper and separating devices, of which two sets are preferably employed arranged upon opposite sides of the central line of the machine. The mechanism of one set of these devices will now be described.

50 is a bracket having a forwardly presented horizontal yoke 51 which embraces the rearwardly presented flange 2^a of the front cross rail 2 of the feeding machine frame. One or more set screws 52 are threaded through the lower arm of yoke 51 and engage the chamfered face 2^b on the under surface of flange 2^a for rigidly securing the bracket 50 in position upon the ma-

chine frame. As shown particularly in Fig. 4 of the drawings, the bracket 50 projects upwardly in rear of the constantly driven shaft 5 between two of the under feed rollers 6 above described, the upper end of bracket 50 being in the form of a U-shaped yoke presenting two bearing arms 55 in which is journaled a short shaft 56 carrying between the arms 55 a circumferentially grooved rubber faced roller 57. This roller 57 is constantly driven in a direction reversely to the direction of the under feed rollers 6, that is, with its upper periphery moving rearwardly toward the pile of sheets. 10 Roller 57 is constantly driven by means of a pinion 58 keyed to the projecting end of its shaft 56 and meshing with a small gear 59 keyed to the constantly driven shaft 5, such a gearing being shown particularly in Fig. 4 of the drawings.

Vertically dovetailed to the rear face of the bracket 50 is a sliding block 60 upon which are mounted a series of fingers 65 set into inclined recesses 61 formed in the block 25 60 and secured therein by set screws 62. The upper ends of these fingers 65 are curved forwardly to present their ends approximately in the plane of feed of sheets, the curvature of the fingers conforming approximately to the curvature of the separator rollers 57. These fingers 65 are presented in the annular grooves of the roller 30 57 for the purpose which will presently appear.

35 The sliding block 60 has pivoted to it at 63 a downwardly presented rod or bolt 66 which passes through a guide lug 67 presented rearwardly in the bracket 50. An expansion spring 68 surrounds the rod 66 40 and is confined between a collar 69 upon the rod and the bracket lug 67, an adjusting nut 70 and binding nut 71 being threaded upon the lower end of rod 66 to permit the vertical movement of the block 60 carrying 45 fingers 65 and for limiting the upward movement of said parts. The adjustment for operation is such that the fingers 65 will be presented a little bit above the upper periphery of the grooved under roller 57, so 50 as to normally prevent the frictional engagement of said roller 57 with a sheet.

The upper caliper member which cooperates with the lower caliper fingers 65 and separating roller 57 is preferably in 55 the form of a roller shown at 75 journaled in the bearings 76 of the yoke 77 which is mounted upon the rear ends of the rock arm 78 journaled upon the cross shaft 79. This shaft 79 is constantly driven through any 60 suitable means from a part of the feeding machine and has keyed to it between the arms 78 a small gear 80 which meshes with a similar gear 81 keyed to an intermediate shaft 82 having mounted upon its projecting end a gear 83 meshing with an interme-

diate gear 84 which in turn drives a gear 85 keyed to the projecting end of shaft 75* of the upper caliper roller 75. By this means the roller 75 is constantly rotated in the same direction as the under roller 70 57 so that their adjacent peripheries—that is, the upper periphery of roller 57 and the lower periphery of roller 75, will move in opposite directions.

Pivots connected with the rocking yoke 75 shaped frame 77—78 is an upwardly extending pitman 90 which is formed with a U-shaped fork or guide 91 which straddles the cam shaft 20 and is confined between the hub of a cam 100 and a collar 101. This 80 pitman 90 carries a lug 92 through which passes an adjusting screw 93 which engages an adjustable block 94 supported against one face of pitman 90 by means of a tap bolt 95 which passes through a vertical slot 85 96 formed in the pitman 90 and is threaded into the adjustable block 94. This block 94 has journaled upon it an anti-friction roller 97 which operates in peripheral engagement with the controlling and operating cam 100. 90

An arm 105 projects rearwardly from stay bar 3 and carries at its end a pin 106 to which is attached the upper end of a spring 107 connected at its lower end to a pin projecting from the rocking yoke-shaped frame 95 77—78. The spring 107 tends to raise the frame 77—78 moving upper caliper roller 75 away from the lower caliper member, the upward movement being limited by the engagement of anti-friction roller 97 with 100 the controlling cam 100. The construction is such that the high portion of the cam 100 positively forces the roller 75 downwardly into a predetermined position, depending upon the position of the block 94 upon pitman 90. 105

As shown particularly in Fig. 4 of the drawings, the upper caliper roller 75 is presented directly above the lower separating roller 57 and the lower caliper 110 fingers 65. As shown particularly in Figs. 2 and 3 of the drawings, the controlling cams 12 and 100 are so arranged relatively that the upper caliper roller 75 will be moved down into operative position and held in 115 that position for a sufficient period to permit the feeding off devices to feed a sheet or sheets beneath it, and that the drop roller delivery mechanism is held out of operation while said caliper and separating action 120 is taking place, and will be thrown into operation immediately after the caliper roller 75 is raised away from the plane of feed. Said caliper roller is intermittently moved out of operation to avoid unnecessary wear, although it will be clear that said roller could be permitted to remain in caliper position continuously without interfering with its operation. As shown in 125

Fig. 9, the upper caliper member may be 130

in the form of a stationary shoe 110 adjustable by any suitable means such as shown at 111 so as to place it in accurate relation to the under caliper members or fingers 65. 5 The operation of a feeding machine with the improved caliper and separating devices applied will be clear from the following explanation: The feeding off devices move into engagement with the top sheet of 10 the pile and feed it forward causing its front edge to engage the lower feed rollers 6 and curved upper portions of lower caliper fingers 65, the upper caliper members or rollers 75 having just previous to the action 15 of the feeding off devices been moved down into caliper position. If a single sheet only has been moved forward by the feeding off devices, the sheet is placed in position for delivery without any action on the part 20 of the caliper and separating devices, the lower caliper fingers 65 supporting the sheet out of contact with the lower separator rollers 57 so that said rollers cannot have any action upon the sheet. When the 25 single sheet reaches proper position for action of the sheet delivery mechanism, the feeding off devices have completed their forward feeding stroke and are raised out of contact with the pile, and at the same time 30 the upper caliper members are raised, the holding down feet are moved into clamping engagement with the pile, and the drop roller delivery mechanism is thrown into action to rapidly feed the sheet from the pile to the 35 sheet conveyor or other mechanism arranged to receive it. If, perchance, the feeding off devices feed forward two sheets from the pile, (it being understood that the upper caliper member is lowered just prior to 40 the action of said feeding off devices), the pressure created by the forcing of the extra thickness of sheets between the upper and lower caliper members will cause the depression of the spring sustained lower caliper members or fingers 65 so as to permit the under sheet to come into frictional 45 contact with the lower separator rollers 57 with the result that this under sheet will be separated from the top sheet and be positively moved rearwardly slightly toward the pile, while the top sheet under the action 50 of the feeding off devices and upper caliper rollers 75 will be moved forward into the position, from which it is immediately 55 afterward delivered by the drop roller delivery mechanism in the manner just explained.

In practice, machines to which the present improvements are applied are usually arranged to feed the successive separated sheets to a conveyor which transfers the sheets to a printing press, folding machine or other machine designed to operate upon them. The sheet conveyors are commonly provided 60 with some form of sheet straightening de-

vices which not only square the sheets upon the conveyor before they reach the gages of the machine to which they are being fed, but also serve to time the arrival of the successive sheets at the gages. This timing of 70 the sheets upon the conveyor corrects any slight inaccuracies in the advancement of sheets from the automatic paper feeding machine caused by some of the sheets projecting forwardly from the pile a little more than others at the commencement of the feeding off operation,—particularly such sheets which have been moved forward with a top sheet and separated and pushed back slightly by the under separator rolls. 75

While our invention has been designed with particular reference to feeding and separating thick and heavy sheets of paper, such as cardboard, it will of course be understood that by reason of the adjustment of 80 the parts, the machine may be set to handle any thickness of sheets so long as there is sufficient stiffness and rigidity in the sheets to permit the feeding off devices to operate upon the sheets in the manner explained. 85

What we claim is:

1. In a paper feeding machine, the combination of a support for a pile of sheets, and a feeding off device operating upon said pile, with a rearwardly feeding roller operating below the plane of feed and over which sheets are passed by said feeding off device, sheet caliper means operating simultaneously with said feeding off device and preventing the action of said roller 90 upon a sheet when a single sheet is passing, and causing the action of said roller upon the under sheet or sheets when more than one sheet is passing, pile holding clamps adapted to engage the pile in rear of the top sheet, and suitable sheet delivery mechanism. 95

2. In combination with the feeding off and sheet delivery devices of a paper feeding machine, a separator roller mounted in stationary bearings below the plane of feed, an upper caliper member movable toward and away from said roller, a yieldingly mounted lower caliper member supported adjacent to the periphery of said roller, and means for operating said roller in the direction to move sheets rearwardly. 110

3. In combination with the feeding off devices the sheet delivery devices and pile holding clamps of a paper feeding machine, a separator roller mounted in stationary 115 bearings beneath the plane of feed, an upper caliper member movable toward and away from said roller, and a yieldingly mounted caliper shoe supported adjacent to the periphery of said roller and means for operating said roller in the direction to move sheets rearwardly. 120

4. In a paper feeding machine, the combination of a pile support, sheet feeding devices operating above said support, drop 125

5 roller sheet delivery mechanism, and a sheet caliper and separating mechanism comprising a lower rearwardly feeding roller supported beneath the plane of feed, an upper forwardly feeding roller supported above the plane of feed, means for raising and lowering said upper roller with relation to said lower roller, and a yieldingly mounted lower caliper member arranged adjacent to said lower roller and adapted to support single sheets out of contact with said lower roller, substantially as set forth.

10 5. In a paper feeding machine, the combination of a pile support, sheet feeding devices operating above said support, sheet delivery mechanism including a constantly driven lower shaft carrying rollers and intermittently operated drop rollers co-operating therewith, a sheet separating roller supported beneath the plane of feed and geared to said constantly rotating shaft to rotate reversely to said under feed rollers, an upper caliper member supported above the plane of feed, in proper relation to said 20 separator roller, and a yieldingly mounted lower caliper member arranged adjacent to said lower separating roller and adapted to support single sheets out of contact with said separator roller.

25 6. In a paper feeding machine, the combination of a pile support, sheet feeding devices operating above said support, sheet delivery mechanism, and a sheet caliper and separating mechanism mounted adj-

35 cent to said delivery mechanism and comprising an annularly grooved separator roller supported beneath the plane of feed, a yieldingly mounted block carrying lower caliper fingers projecting into the annular grooves of said separator roller and supported above the periphery of said separator roller, and an upper caliper member supported above the plane of sheets and movable toward and away from said lower caliper fingers.

40 7. In a paper feeding machine, the combination of a pile support, sheet feeding devices operating above said support, sheet delivery mechanism, pile holding clamps, and a sheet caliper and separating mechanism comprising a lower roller supported beneath the plane of feed, an upper roller supported upon a rock arm above the plane of feed, means for raising and lowering said upper roller with relation to said lower roller, 45 means for driving said rollers to cause their adjacent peripheries to move in opposite directions, and a yieldingly mounted lower caliper member arranged adjacent to said lower roller and adapted to support single 50 sheets out of contact with said lower roller, substantially as set forth.
